UNITED STATES PATENT OFFICE.

WILLIAM N. WHITELEY, OF SPRINGFIELD, OHIO.

IMPROVEMENT IN HARVESTERS.

Specification forming part of Letters Patent No. 77,691, dated May 5, 1868.

To all whom it may concern:

Be it known that I, WM. N. WHITELEY, of Springfield, in the county of Clarke and State of Ohio, have invented a new and useful Improvement in Harvesters; and I do hereby declare the following to be a full, clear, and exact description of the same, reference being had to the accompanying drawings, in which—

Figures 1 and 2 are perspective views of my machine from front and rear. Fig. 3 is a plan view of the same. Fig. 4 is a rear elevation of the same. Fig. 5 is a side elevation of the same. Fig. 6 is a plan view, showing the gearing, platform removed. Fig. 7 is a sectional side elevation on line $\alpha\alpha$, Fig. 6. Fig. 8 is a rear elevation, showing the cutting apparatus elevated from the ground. Figs. 9, 10, 11 are views of the guideway and rake and reel-shaft. Fig. 12 is a sectional elevation of the rear end and lug of the inner shoe, showing the drop-latch.

This invention relates to a combined reaping and mowing machine; and it will be fully understood by reference to the following description and the accompanying drawings, in which the same letter indicates the same part in all of the figures.

A is the main frame, which I cast in one piece, chambered in such form as to receive the mechanism and protect it perfectly from accidental blows, from dust and dirt, and without any waste room.

Mounted in proper boxes, B B, secured to the upper edge of the main frame A, is the main shaft O, upon the outer ends of which are the bearing-wheels D.

A ratchet and pawl are placed within a hub, E, and the one secured to the shaft, while the other is secured to said hub. This permits the wheel to revolve freely backward upon the shaft, as it is necessary that it should do, in backing the machine, or when in turning at the corner of the field one wheel is nearly or quite stationary while the other continues to revolve.

Upon and rigidly secured to the main shaft C, and within the shell of the main frame, is the internal-gear wheel F, whose pinion is in front and mounted at the end of the pinion-shaft G, which runs in boxes H, secured to the upper edge of the main frame A. The pinion-shaft is back-geared to the bevel-driver I, which runs loosely upon the main shaft C, and gears

with the cutters' crank-shaft J, which lies in a long shell-box, K, bolted to the main frame, as shown. It will be observed that by back-gearing in this manner speed is gained with the use of small wheels and with no more shafting or greater number of bearings than though the bevel-driver should be placed directly upon the pinion-shaft.

In front of the gearing a compartment, L, is formed in the shell of the main frame, to serve as a receptacle for tools. The cover or platform M is also cast in metal and formed to meet the upper surface of the main frame all around, and thus inclose all of the gearing of the machine.

The driver's seat N is mounted upon the cover or platform M upon the spring-leg O, which may be moved forward or backward and secured at any point by means of a slot and screw-bolt in the ordinary manner.

The cover M is hinged to the front end of the main frame, as shown at P. To gain access to the tool-box or to the machinery inclosed within the shell of the main frame the platform M is turned up on its hinge, as shown in Fig. 7.

The pinion of the wheel F is nicked across one of its ends to receive a clutch-pin which projects through the pinion-shaft G, and by moving the said pinion slightly in the direction of the length of the shaft G it may be relieved from the clutch-pin, and thus throw the working mechanism out of connection with the driving-wheels. The pinion may be thus moved out of or into connection by means of the clutch-lever Q, which is located convenient to the foot of the driver.

The drag-bar R is secured to the front end of the main frame, as shown at S, from whence it bends downward and backward, passing under the main frame and between the driving-wheel, and finally at its rear end it is divided and bent outward so as to reach the shoe T of the cutting apparatus. Said shoe T is attached to the two parts of the rear end of the drag-bar by screw-bolts, which pass through said parts and into lugs cast on the shoe for that purpose.

The shoe T is maintained at the proper lateral distance from the crank-shaft by the coupling-arm U, which is secured at one of its ends to the drag-bar near the shoe and at its other end around a hub on the crank-shaft box, so that as the shoe may rise and fall with the undula-

tions of the ground the linear distance between said shoe and the axis of the crank-shaft will remain unchanged. The coupling-arm *U* is retained on the hub of the crank-shaft box by means of a hooking-flange, which projects from the box and overlaps the end of the coupling-arm, so that it cannot move laterally unless it be turned so far on its seat as to withdraw the end entirely from beneath said flange.

The standard *V* is rigidly secured to the box of the crank-shaft, or it may be cast in one piece with said box. The top of said standard curves over sidewise toward the cutting apparatus, and it is slotted to receive the lever *W*, which is securely bolted to the coupling-arm *U*. The head of the standard *V* is perforated with a number of holes, through either one of which an adjusting-pin, *X*, may be inserted to secure the lever *W* at the desired point. When said adjusting-pin is inserted through one of the holes in the standard *V* and through a corresponding hole in the lever *W*, then the coupling-arm *U* is made rigid at its joint upon the crank-shaft box, as said coupling-arm will then be attached at two points instead of one.

When the adjusting-pin *X* is withdrawn from its place in the head of the standard the lever *W* may be used to elevate the cutting apparatus from the ground by pressing downward upon its outer end, which projects beyond the crank-shaft for that purpose, and is so arranged that the driver may conveniently reach it while on his seat. This use of the lever *W* will only occur when the machine is being used as a mower and when it becomes necessary to raise the cutting apparatus to pass over some obstruction in the road.

By means of the adjusting-pin *X* the inner end of the cutting apparatus may be retained at the desired degree of elevation from the ground while reaping. I also arrange another brace, *Y*, which is bolted to the coupling-arm at one end, while the other end passes freely through the head of the stud *Z*, and may be secured at any point therein by an adjusting-pin which passes through the same. Either one of these devices will retain the shoe *T* at the desired distance from the ground.

The tongue *a* is pivoted to the side of the shell of the main frame by the bolt *b*, and its angle to the main frame may be adjusted by the adjusting-bolt *c*, which may be inserted through the tongue into one of a series of holes, *d d*, which are made in a flange, *e*, at the forward end of the shell of the main frame.

The cutting apparatus is constructed in the usual manner with open guard-fingers and reciprocating cutters. At its outer end is a metallic shoe with a vertical longitudinal flange, to the outer side of which the divider is bolted. An adjustable caster-wheel is hinged to a plate, which is secured to said flange by bolts passing through said plate and the divider.

The standard *f* is mounted upon the shoe *T*, and secured thereto by screw-bolts. It stands upon the shoe inclining backward slightly, and

its upper end is bent so as to be horizontal, and upon this portion the hollow post *g* is secured by suitable bolts. Through the hollow post *g* the reel and rake-shaft *h* passes, and at the top of said hollow post is bolted the rake and reel-guide *i*. The reel-guide *i* is formed so as to conduct the reel and rake-blades over the platform and cause them to rise up into the air as they pass over the main frame and driver's seat. The rake and reel-arms are pivoted to a head, *k*, which is keyed fast to the top of the shaft *h*. On the side of each of the reel-arms *l* is a plate of metal, *m*, having a pendent arm, *n*, and traveling roller *o*. The roller *o* travels over the guide-frame *i* as the rake revolves, and as the guide-frame rises above the horizontal in its configuration the rake or reel-arm must rise correspondingly. The guard *p* is placed around that part of the guide-frame which is traversed by the rollers *o* when the reel-blade is descending upon the platform, so as to compel the rake or reel to press down into the grain upon the platform. The guard *p* is a plate placed parallel with the surface of the guide-frame, and connected thereto by a flange, leaving sufficient space between the surface of the guide and the surface of the guard to permit the passage of the rollers *o*.

It is not desirable that each one of the reel-blades should descend close enough to the platform to remove the grain thereon. I therefore attach to the guard-frame on that side toward the platform a switch, *q*, which, when closed, lies with its point against the guide-frame, so that the traveler is diverted and passes over the switch instead of along the guide-way. The passing over the switch prevents the reel-arm from descending to the platform. The switch *q* is pivoted to the guide-frame by a small stud, which passes down through a suitable hole in said frame, and has at its lower end a short arm, *r*, against which the spring *s* presses in such a direction as to open the switch when not restrained.

At a little distance in the rear of the stud by which the switch *q* is pivoted to the guide-frame is another stud, *t*, which projects downward from said switch through a slot in the guide-frame, and when the switch is closed a latch or stop, *u*, engages with the stud *t* and holds the switch closed. The latch *u* is a stiff bar of metal pivoted at one end to the under side of the guard-frame at *v*, and its free end supported by the spring *s*, which lifts said latch and also operates the switch, as above described. The rear end of the switch is bent inward, as shown at *w* in Fig. 9, so that when one of the travelers *o* passes behind said switch and descends upon the platform to remove the grain therefrom the traveler will come in contact with the bent end *w* and push it back, so as to close the switch and permit the latch *u* to engage with the stud *n* and hold the switch closed, and this will be done in time to divert the next succeeding traveler and cause it to pass over the switch and raise the reel-blade from the platform.

The latch *u* has a cord, *a'*, attached to it at a point near its free end, and this cord passes downward through a dead-eye or around a small pulley at *b'*, and thence forward to a treadle, *c'*, convenient to the driver's foot, so that when the machine is in operation the latch is closed and the reel-blades all pass at a distance above the platform until grain sufficient for a gavel has accumulated, when the driver presses the treadle and withdraws the latch *u*. The spring *s* instantly opens the switch and the next succeeding traveler passes behind it, and the reel-blade descends to the platform and sweeps the grain therefrom, closing the switch in its passage, to remain closed until the driver desires the rake to operate again.

The pulley *k'* is secured to the main shaft either rigidly or with a ratchet-and-pawl connection, as may be preferred, and by means of a chain or belt, *m'*, which passes around it and connects it with the corresponding pulley, *n'*, secured to the lower end of the shaft *h*, motion is communicated to the reel and rake.

A guide, *q'*, may be employed to lead the belt properly up to the pulley *n'*, as shown.

The joint at the heel of the cutter-bar is made by a forked pitman and conical or conoidal journals. The parts of the pitman are drawn together and adjusted by the screw-bolt *g'*, with the jam-nut *h'* placed between the parts, so that it may hold the main nut secure without any danger of working loose by concussion, and also without danger of altering the tension of the joint.

The drop-latch *i'* is pivoted to the shoe in such a manner that its free end will drop behind the heel of the cutter-bar and will prevent the cutter-bar from running out of its seat when the cutting apparatus is folded for transportation to and from the field, and when said free end is raised up the cutter-bar may without trouble be withdrawn for purposes of repair, &c. This latch is perfectly automatic, and consists of only one piece, without springs or other devices, which would render it more complicated or increase its liability to fail.

Having described my invention, what I claim as new is—

1. The shell main frame *A*, cast in a single piece, with a recess fitted to receive the gearing, and another recess, *L*, to serve as a receptacle for tools, in connection with the cover or platform *M*, likewise cast in a single piece, so as to inclose the gearing and cover the toolbox with the same piece, substantially as set forth.
2. The drag-bar *R*, constructed and attached to the frame and shoe in the manner described, in connection with the brace *Y*, and the standard *Z* and coupling-arm *U*, as set forth.
3. The lever *W*, attached and operating as set forth.
4. The drop-latch *i'*, constructed and located as described.
